(54) **ASBESTOS, USE & APPLICATION OF, TO
STOVES, GRATES, CRUCIBLES, &C.**

(76) Inventor: **John Scott**

John Scott

126.

The Schedule referred to in these Letters Patent and making part of the same containing a description in the words of the said John Scott himself of his improvement in the use & application of Asbestos. It is known to all to whom it may concern that I John Scott of the City of Philadelphia in the Commonwealth of Pennsylvania have invented a new and useful improvement in the use and application of the uncomminable substance asbestos in the construction of Crucibles, stone-Cylinders, grate-backs and jambes and furnaces. Which improvement I describe as follows. Let the asbestos be mixed with mineral substances pulverized and moistened so as to form a thick Clay, such as flint-clay, soap-stone, black-lead and fine clay and then let the mass be hardened by the action of heat or by gradual drying. It may be made of almost any size or shape and is especially useful for Crucibles, stone-Cylinders, grate-backs or jambes and furnaces. The asbestos thus applied will contribute also to the incorabstiblity, firmness and durability of the article. The use and application of it in this manner and for these purposes, I claim as my own improvement. In testimony that the above is a true specification of my said improvements, I have hereunto set my hand and seal this ninth day of October (A.D.) 1835.
